UNITED STATES PATENT OFFICE.

WILLIAM GLANZER, OF DAYTON, OHIO, ASSIGNOR OF ONE-HALF TO JACOB D. HEATER, OF SAME PLACE.

FRUIT-CAN.

SPECIFICATION forming part of Letters Patent No. 565,679, dated August 11, 1896.

Application filed May 5, 1896. Serial No. 590,298. (No model.)

To all whom it may concern:

Be it known that I, WILLIAM GLANZER, a citizen of the United States, residing at Dayton, in the county of Montgomery and State 5 of Ohio, have invented certain new and useful Improvements in Fruit-Cans; and I do hereby declare that the following is a full, clear, and exact description of the invention, which will enable others skilled in the art to 10 o which it appertains to make and use the same, reference being had to the accompanying drawings, and to the letters of reference marked thereon, which form a part of this specification.

15 My invention relates to improvements in fruit-cans, the features of which will be fully hereinafter described and claimed. My invention involves a tin can adapted for sealing with wax; and the object is to aid in the 20 unsealing by using a detachable flange which may carry the sealing-wax with the cover on opening, and thereby prevent the melted or softened wax from running out and possibly dropping into the contents of the can. The 25 object is accomplished by the construction illustrated in the accompanying drawings, in which—

Figure 1 is a side elevation of the can with a portion cut away of both the fixed and movable flanges. Fig. 2 is a top view of the movable flange.

The letters designate like parts in the two views.

The tin can is constructed as usual, and 35 comprises the body A, the cover B, and the fixed flange D, soldered to the side of the body.

The movable flange C is formed to pass freely over the top of the can, and its normal position is resting on said fixed flange. The flanges are alike in form and may have any suitable 40 angle to the body of the can. Between the lower edge of the cover and the inner edge of the movable flange there is the space of about one-eighth of an inch.

In use, the movable flange is placed on the 45 fixed flange, the top is placed in position, the melted wax is poured into the space between the cover, the exposed part of the body, and said movable flange, and the can is hermetically sealed.

To open the can, the wax is rendered soft by heat, the movable flange is raised against the under edge of the top, and they are both lifted off together, thus carrying the wax with the cover, and thereby preventing any dropping and consequent waste.

Having fully described my invention, what I claim, and desire to secure by Letters Patent, is—

The fruit-can comprising the body, top and 60 flaring fixed flange in combination with the movable flange held on said fixed flange adapted to engage the under edge of the rim of said top, substantially as shown and described.

In testimony that I claim the foregoing as my own I affix my signature in presence of two witnesses.

WILLIAM GLANZER.
